UNITED STATES PATENT OFFICE.

CARL A. PORATH AND GEORGE N. WILLIAMS, OF KOKOMO, INDIANA, ASSIGNEES OF ONE-HALF TO KOKOMO STEEL AND WIRE COMPANY, OF KOKOMO, INDIANA, A CORPORATION OF INDIANA.

NAIL-FORMING MACHINE.

Application filed July 11, 1922. Serial No. 574,146.

To all whom it may concern:

Be it known that we, CARL A. PORATH and GEORGE N. WILLIAMS, both citizens of the United States, residing at Kokomo, in the county of Howard and State of Indiana, have invented certain new and useful Improvements in Nail-Forming Machines, of which the following is a specification.

The machine of this invention is intended primarily to cut and form a wire nail having a wide flat head of a character suitable for the fastening of felt composition or similar roofing materials which require either a wide headed nail or a tin washer in order to secure sufficient gripping contact to prevent tearing away of the roofing material, although the machine is equally adapted for the manufacture of screws and bolts as well as nails.

The present invention is designed to produce such a nail having a head diameter greater than that which can commonly be produced by machines of the types which have come under our observation, thereby in most cases eliminating the necessity for the use of washers in connection with the nails so produced.

In the formation of a wire nail, it is customary to feed forward a length of wire sufficient to form the head and shank of the nail and thereafter grip the wire within dies, and then subject the projecting portion to the compressive action of a former, which upsets or distorts the metal laterally to produce a flat head. The capacity of the metal to respond, when cold, to such distorting forces is limited, and if exceeded will result in a rupture of the metal and a corresponding impairment of the head.

The present invention centers primarily around the provision of a forming head or die which performs the upsetting action in two operations instead of one, which has heretofore been the customary practice in so far as our observation has extended. In the first upsetting operation the forming die engages the projecting wire blank in a cupped or recessed portion of the head, which serves to distort or upset the metal to a limited de-

gree, forming thereon a somewhat elongated and considerably enlarged preliminary head. The die or forming head then retreats sufficiently to clear the preliminary nail head thus formed, and is then turned sufficiently to present a flat or uncupped surface to the partially formed nail head, so that upon the second advance of the former the initially distorted metal will be compressed and flattened to the desired degree without disruption, thus completing the formation of the nail head in two stages rather than one.

The invention also relates to the means provided for supporting and backing the forming tool, so that the reaction of its thrust against the wire blank will be adequately withstood without throwing this load upon the working or power transmitting portions of the mechanism. This is a matter of great importance in machinery of this character, in which it is customary to apply loads amounting to several tons to the forming head or die, which loads, if they react upon the operating or rotating portions of the mechanism, tend to cause excessive wear or possible breakage.

The invention further relates to the means for gripping the wire blank during the nail forming operation, and to the means for operating the grippers in such manner as to reduce the thrust and wear on the operative portions of the mechanism, and to the features of construction and combination of parts hereinafter described and claimed.

In the drawings:

Figure 1 is a top or plan view of the entire machine;

Fig. 2 is a side elevation, with the driving pulleys partially broken away;

Fig. 3 is a cross sectional elevation on line 3-3 of Fig. 2, looking in the direction of the arrows;

Fig. 4 is an enlarged side elevational detail of the mechanism for clamping, cutting and forming the nail head, together with the cams for actuating the same;

Fig. 5 is a plan view of the cam shaft, cams and associated parts;

Fig. 6 is an enlarged detail showing the

face of the anvil, the cutters, and associated parts;

Fig. 7 is an enlarged cross sectional detail of the means for rocking the shank of the former die head;

Fig. 8 is an elevation partly in section of the former die head and associated parts;

Fig. 9 is a face view of the same mechanism;

10 Fig. 10 is a section through the toggle joint of Fig. 8;

Fig. 11 is a face view of the wire, clamping plates, and associated mechanism;

15 Fig. 12 is a view showing the former head and anvil in the act of forming the preliminary conical head on the nail blank;

Fig. 13 is a similar view showing the same mechanism in the operation of flattening the previously formed conical nail head;

20 Fig. 14 is a perspective view of one of the completed nails; and

Fig. 15 is a detail of the feeding gripper.

The machine as a whole is mounted upon a bed plate 20 of massive construction, provided at its forward end with an upstanding table frame 21, and at its rear end with a back frame 21^a, both of which portions of the structure are of massive formation to accommodate the heavy thrusts imposed in forming the nail head.

35 The forward end of the machine, that is to say, the end at which the wire enters, is provided with a suitable flat table plate 22 which furnishes an elevated support for the positioning of the mechanisms most intimately or immediately concerned in the feeding, clamping, forming and cutting operations which follow in the sequence named; that is to say, the wire coming from the reel is fed 40 forward to the degree requisite to allow of the protrusion required to accommodate the upsetting of the head; next follows the clamping of the wire in this position; next follows the two head forming operations; 45 and finally the completed nail is severed and delivered.

50 The wire coming from the reel passes through a straightener 23 of the usual character, comprising a plurality of staggered straightening rolls 24, which straightener is bolted or otherwise secured to the extreme forward end of the supporting table 22. From the straightener the wire passes to the feeding gripper 25, which comprises a slidably mounted reciprocating carriage 26, which has mounted thereon a gripping head consisting of a pair of spaced jaw members 27, one of which is slotted on its inner face to receive a ball 28 the slot at the outer end being tapered, so that, on the forward or inner movement of the gripper, the ball will ride up on the inclined rear end of the slot and be forced into gripping relation with the wire, while on the return movement the ball will ride freely into the deep-

er end of the slot and slip freely along the wire preparatory to the taking of the next succeeding grip thereon. The means for imparting reciprocation to the feeding gripper will be later described.

70 The wire pushed forward by the feeder enters an aperture 29 in a heavy anvil block 30 rigidly mounted upon the table 22, which anvil block is recessed to house a center block 31 provided with a reduced registering aperture 32. The anvil block 30, on its rear face, is provided with a cross recess having upper walls 33 and lower walls 34, the latter of which is downwardly beveled to afford an undercut, which undercut co-operates with a similar beveled edge on a gib 35 seated against the top wall 33 in affording an undercut guide channel for the housing of aligned fixed and movable clamping jaws 36 and 37, each of which is provided on its inner face with a half circular serrated recess 38, so related that when the jaws are brought together they will furnish a cylindrical serrated bore within which the wire is rigidly clamped against recession when subjected to the heavy pressure of the forming die. The formation of these parts is best illustrated in Figs. 11, 12 and 13, from which it will be seen that the gibs 35 are secured in place within the anvil block by means of bolts 39, 85 adjustable set screws 40 being provided to lock the gibs tightly in position.

80 The movable jaw is forced inwardly by contact of an adjustable screw stop 41 entered through a lug 42 on the inner corner of a lever arm 43 (see Figs. 1 and 11), which is pivoted to a post 44 upstanding from the table at a point forwardly and to one side of the anvil block. A spring 45 secured to the lever arm tends to retract the 90 same, and the lever arm on its outer edge is recessed to afford a housing for a roller 46 which co-operates with a fixed roller 47 journaled between a pair of lugs 48 upstanding from the corner of the table. Between the rollers is located a vertically movable wedge 49 carried by a shank 50, which at recurrent intervals will be thrust upwardly between the rollers, thereby rocking the lever arm on its pivot and causing the movable clamping jaw 37 to engage the wire. Since only a slight positive action is required to retract the movable jaw, a wire connection 51 is provided between the lug 42 and the movable jaw which serves to retract the 100 latter when the lever arm is pulled back upon the recession of the wedge by the action of the spring 45.

105 Immediately behind and in alignment with the anvil is located the former die 52 (see Figs. 8, 9, 10, 12 and 13), which die is in the form of a cylindrical hammer head having a flat face 53, and the head is provided with an eccentrically positioned bore 54 which receives a forming tool 55 pro-

vided in its forward end with a conical recess 56 of a size and shape to engage and upset the protruding end of the wire in the preliminary forming operation. The 5 center of the recessed forming tool 55, when in operating position, is coincident with the wire line which brings the center of the forming die slightly above the wire line. It is to be observed, however, that by slightly 10 turning or rotating the forming die a flush or unbroken surface will be presented to the wire line, and this is the method of operation followed in preparation for the final advance of the die against the partially 15 formed nail head, which is flattened out or widely distended during the final operation.

The forming die is secured to the end of a shank 57 by means of a screw coupling 58, which shank is of heavy and rugged 20 formation and is socketed within and protrudes from the forward end of a reciprocating cylindrical slide block 59, being locked therein by means of a pair of set screws 60. The slide block 59 is slidably 25 mounted within a cylindrical bushing 61 carried within a bored head 62 upstanding from a base plate 63, which is bolted or otherwise secured to the table plate 22 (see Fig. 7).

The slide block 59 has entered therethrough a cross bar 64, the ends of which protrude on opposite sides and constitute outstanding wings which are entered through registering slots 65 and 66 in the bushing 30 and head respectively, which slots are elongated to permit the necessary reciprocation of the cylindrical block during its advance and recession toward and from the anvil block, and are of lateral dimension sufficient 35 to permit of the limited rocking movement necessary in bringing the recessed forming tool into and out of coincidence with the wire line during the first and second stages 40 of the forming operation.

The bed plate 62 has depending therefrom a pair of slotted guide lugs 67 which extend through the table plate 22 and afford a 45 slideable mounting for a pair of oppositely disposed companion push bars 68, the upper 50 ends of which are sufficiently elongated, fore and aft, to engage the lateral wings of the cross bar 64 in all fore and aft positions of the latter's adjustment, and these push bars are adapted to move vertically in alternation 55 to one another so as to impart rotative movements to the cylindrical block in timed relation to the advance and recession thereof, and these push bars are pivoted to links 69 provided with adjustable turn buckles 60 70, which links are adapted to be actuated by means presently to be described. The push bars are adjusted to rigidly hold the forming die against turning during the two nail forming operations which is essential

in order to present the intended portions of 65 the die to the wire line.

The rear end of the slide block 59 is recessed to receive a bearing block 71, held in place by a threaded bushing 71^a, which bearing block is bifurcated to receive the forward end of a toggle link 72, which is pivoted thereto by a pivot pin 73 (see Fig. 10). The rear end of the toggle link is pivoted to the forward end of a thrust link 74, which in turn is pivoted at its rear end with 75 in a bifurcated adjustable bearing head 75 by means of a pivot pin 76, the bifurcated bearing head being socketed within a recess 77 in the top of the massive rear frame 21^a, which portion of the structure is reinforced 80 by the provision of a pair of tie rods 78 entered through lugs 79 located on opposite sides of the rear frame, which tie rods extend longitudinally of the machine and are anchored at their forward ends 80 to the 85 forward frame so that the thrust imparted to the rear frame by the action of the toggle mechanism is distributed in part to the forward portion of the machine.

In order to adjustably anchor the bearing 90 head 75 within the rear frame, the shank 81 of the bearing head is provided with a tapered cross slot which receives a wedge bar 82 on opposite sides of the head of the frame, and the reduced end of the wedge bar 95 terminates in a threaded stem 84 which receives a nut 85 which may be tightened to hold the wedge in adjusted position after it has been driven to place. The shank of the bearing head terminates in a threaded 100 stem 86 which receives a nut 87 bearing against a washer 88 which contacts the rear face of the rear frame head, thus providing for the longitudinal adjustment of the toggle. 105

The relation of the toggle link 72 to the thrust link 74 is such that the blow on the die head will be delivered when these two 110 toggle members are in their straightened or aligned position, so that the line of reaction will coincide with the axial alignment of these toggle members, and this thrust will be received against the rugged rear portion of the machine, which is constructed in such a way as to afford abundant resistance to this 115 thrust, which is extreme in the practical operation of the machine.

The thrust link 74 is downturned and pivoted by a cross pin 89 within the bifurcated upper end 90 of an operating arm 91 which 120 is directly pivoted upon a wrist pin 92 forming part of a crank 93 carried by a cam shaft 94 (see Fig. 5). This cam shaft constitutes the driving element for operating the various mechanisms heretofore described, in timed relation to one another. The cam shaft is mounted within outer journals 95 carried by the side walls of the 125

main frame at a point intermediate its ends, and inner journals 96 oppositely located in close proximity to the crank 93. The cam arrangement is illustrated in Figs. 4 and 5. 5 Feeding grippers mounted on the sliding carriage 26 are reciprocated by the action of a longitudinally extending pitman 97 which is pivoted at its forward end to the outer end of the carriage and is pivoted at 10 its rear end to a pivot block 98 which is adjustable within a slot 99 in a swinging lever arm 100 rigidly secured at its lower end to the outwardly protruding portion of a stub shaft 101 journaled through the side of the 15 frame, which shaft at its inner end carries upper and lower arms 102 mounting rollers 103 which coact in alternation with companion cam elements 104 on the cam shaft, which arrangement affords positive back and 20 forth movements to the pitman, in timed relation to one another.

For operating the jaw 37, the shank 50 which carries the wedge head 49 is pivoted at its lower end on a pin 105 within the bifurcated end 106 of a rocking lever 107 carried by a fulcrum 108 socketed within a mounting 109 in the side of the frame, and the rear end of the lever 107 is forked to afford an upper inwardly offset arm 110 and a lower plane arm 111, which arms terminate in bifurcated heads 112 and 113 respectively, each carrying a roller 114. The two rollers ride upon companion oppositely acting cam elements 115 and 116, the former 25 of which operates to throw up the wedge and thereby close the grippers, and the latter of which effects a release thereof.

The links 69 which operate the push bars 68 for imparting tilting or rocking to the die head are pivoted at their lower ends to the 40 forward ends of levers 117 and 118, which levers, being of the first order, are fulcrumed upon the opposite ends of a centrally supported transversely extending stub shaft 119. The forward ends of the respective levers are inturned toward the longitudinal center of the machine (see Fig. 5) to accommodate the position of the links with 45 which they connect, and the rear ends are bifurcated to receive a roller each, which rollers engage the under faces of oppositely acting cams 120 and 121 respectively, which afford the alternating movements required.

The final severing of the completed nail 50 is effected by the means shown in Fig. 6. These means comprise oppositely disposed cutters 122, each carried by a slide plate 123 mounted in a housing 124 secured to the table plate 22 at a point slightly to the rear 55 of the anvil surface upon which the nail head is formed, so that, after the completion of the nail head, the wire will be advanced sufficiently to provide a completed nail and a sufficient amount of protruding wire to 60 provide for the formation of the next suc-

ceeding nail head. Each slide plate 123 is provided near its outer end with a diagonally disposed slot 125, beyond which the plate terminates in a cylindrical guide stud 126 slidably mounted within a guide block 127 70 secured to the table plate. In and out motions of the coacting cutters are afforded by up and down movements of a pair of vertically disposed slide bars 128 mounted in guide plates 129, each of which slide bars is provided near its upper end, on its face, with a roller 130, which rollers engage the diagonally disposed slots in the respective slide plates 123 and effect reciprocations thereof. Each slide bar 128 has pivoted to its lower end a link 131, to which links, in turn, are pivoted, respectively, a pair of rocker arms 132 and 133 rigidly mounted upon a transversely extending rock shaft 134 (see Fig. 5), suitably journaled at its ends to the 75 frame of the machine.

The rocker arm 132 has rearwardly extending therefrom an actuating lever 135, which is bifurcated at its rear end to afford a lower arm 136 and an upper offset arm 137, each of which carries a roller 138. The roller on the lower arm is engaged by a cam element 139, while the roller on the upper arm engages an oppositely acting cam element 140, for effecting the cutting and return movements in timed relation. It will, of course, be understood that the various cams are carefully configured to accurately time the various operations in proper sequence to one another, and since the cutting of cams is a feature of design well understood by those skilled in the art of machine construction, it is not deemed necessary to further delineate the cam construction.

In operation, the wire threaded through the straightening rolls is carried through the feeding grippers and through the clamping jaws, and the machine is then started, after which the nail forming operation will proceed continuously and automatically. Sufficient wire stock is projected to the gripping jaws to form the head of a nail, after which, in timed relation, the gripping jaws will be clamped by the action of the wedge head, which rocks the gripping arm 43 inwardly under heavy compression, and with it the movable clamping jaw, in conjunction with the fixed jaw, bites into the wire, thereby forming the necessary serrations in the nail shank, and at the same time gripping the wire against the subsequent action of the die head.

The die head next advances with the cupped forming tool presented to the wire line, and under the heavy thrust of the toggle mechanism, resisted by the massive frame of the machine, the initial heading operation is performed, with the parts in the position indicated in Fig. 2. Thereafter a quarter rotation of the driving shaft 94 serves to 125 130

retract the die forming head which is concurrently tilted or rotated to the degree necessary to present a flat or uncupped surface to the wire line, so that, with the continued rotation of the shaft through the next ninety degrees, the toggle members will be again drawn into alignment and a final heading thrust imparted to the die head, which hammers down and spreads out the preliminary headed nail stock to form a broad flat head of the character indicated in Fig. 14. The continued rotation of the shaft again retracts the forming die from the now completed nail, and the cutters advance and sever the nail, leaving sufficient stock protruding to provide for a subsequent operation. Concurrently with the cutting of the completed nail, the tilting devices operate to tilt or rock the die forming head to again present the cupped forming tool to the wire line, and the operation proceeds uninterruptedly in the manner stated.

It will be observed that all of the operations above defined are performed under the positive action of the cams, save only the release of the gripping jaws, which is effected by the tensioning of the spring 45. The clamping and heading devices are both actuated by means which serve, at the critical moment, to impose the reactive thrusts against rugged and substantial portions of the structure, so that the cams, journals and rotating parts generally are relieved in large measure from excessive burdens, which would tend to cause wear and deterioration of the mechanism.

The toggle arrangement is so designed that it gives two blows with each rotation of the crank, and these blows are delivered with the toggle in straightened or aligned position so as to relieve the crank from the reaction at the instant of striking.

Although the device has been described with particularity as to detail, it will be understood that the general arrangement of the machine may be varied or modified within a considerable range without departing from the spirit of the invention.

We claim:

1. In a nail forming machine, the combination of means for feeding a section of nail stock, a cupped rotatably mounted longitudinally movable die member, means for longitudinally moving the die member and oppositely disposed push bars engaging the die member in all positions of longitudinal movement for rocking the same and holding the same in adjusted position during the nail forming operations, substantially as described.

2. In a nail forming machine, the combination of means for feeding forward a length of nail stock, grippers for engaging said nail stock, a rotatably mounted reciprocating header provided with a dished sur-

face and with a flattening surface, means for initially rotating the header to bring the dished surface to the wire line to form a preliminary head and for thereafter rotating the header to present a flattening surface to the wire line to spread the preliminary formed head laterally, and means for reciprocating the header, substantially as described.

3. In a nail forming machine, the combination of means for feeding forward a length of nail stock, grippers for engaging the nail stock, a rotatably mounted reciprocating former provided in its acting end with a dished surface and a flattening surface, laterally extending wings on the former, alternately reciprocating members for engaging said wings in all positions of reciprocation thereof, and means for reciprocating the former, substantially as described.

4. In a nail forming machine, the combination of means for feeding forward a length of nail stock, grippers for engaging the nail stock, a rotatably mounted reciprocating former provided in its acting end with a dished surface and a flattening surface, laterally extending wings on the former, alternately reciprocating members for engaging said wings in all positions of reciprocation thereof, and toggle devices for reciprocating the header, substantially as described.

5. In a nail forming machine, the combination of feeding devices for recurrently advancing the nail stock, an anvil block through which the nail stock is fed, fixed and movable gripping jaws mounted within the anvil block, a rocking lever provided with a contact for the movable jaw, a reciprocating wedge element for recurrently acting upon the rocking lever, a rotatably mounted reciprocating header provided in its acting face with a dished surface and a flattening surface, means for rocking the former to alternately present the dished surface and the flattening surface to the wire line, a cam shaft provided with a cranked portion, cams and connections for operating the feeding, gripping and former tilting devices in timed relation, toggle devices for reciprocating the former, and a pitman connecting said toggle devices with the cranked portion of the cam shaft, substantially as described.

6. In a nail forming machine, the combination of feeding devices for recurrently advancing the nail stock, an anvil block through which the nail stock is fed, fixed and movable gripping jaws mounted within the anvil block, a rocking lever provided with a contact for the movable jaw, a reciprocating wedge element for recurrently acting upon the rocking lever, a rotatably mounted reciprocating header provided in its acting face with a dished surface and a

flattening surface, means for rocking the former to alternately present the dished surface and the flattening surface to the wire line, a cam shaft provided with a cranked 10 portion, cams and connections for operating the feeding, gripping and former tilting devices in timed relation, toggle devices for reciprocating the former, a pitman connect-

ing said toggle devices with the cranked portion of the cam shaft, and a rigid backing 10 for the toggles, the latter being designed to stand in aligned relation to the wire line at the instant of heading, substantially as described.

CARL A. PORATH.
GEORGE N. WILLIAMS.
